UNITED STATES PATENT OFFICE.

HENRY J. JACOBS, OF BUFFALO, NEW YORK, ASSIGNOR TO BUFFALO LOUNGE COMPANY, OF BUFFALO, NEW YORK.

SOFA-BED.

1,030,731.

Specification of Letters Patent. Patented June 25, 1912.

Application filed February 7, 1912. Serial No. 676,148.

To all whom it may concern:

Be it known that I, HENRY J. JACOBS, a citizen of the United States, residing at Buffalo, in the county of Erie and State of New York, have invented a new and useful Improvement in Sofa-Beds, of which the following is a specification.

This invention relates to sofa beds or convertible couches of that kind having a seat 10 hinged so that it can be swung forwardly to an inverted position in front of the stationary couch frame, and a folding spring bed bottom which, together with the mattress supported thereby, folds beneath the couch 15 seat when the latter is in its normal position and is unfolded to form a full width bed when the couch seat is inverted. Two features are essential in these sofa beds to make them practicable and desirable. The folding bed bottom or mattress support should be so constructed and mounted that when it is unfolded or extended for use as a bed, it will be supported far enough above the 20 inverted seat and the couch frame to adapt the spring fabric to yield to the extent necessary to insure an easy, comfortable bed; and the bed bottom when folded beneath the couch seat should afford ample space between its sections to accommodate the folded mattress. Sofa beds of this type which 25 secure these results have been patented, but either the folding bed bottoms thereof have been made in three sections, or the constructions, in other respects, have been complicated and expensive and more or less objectionable in use. In a copending application a sofa bed of this sort is described in which the outer section of the folding bed bottom is fixedly mounted on the underside 30 of the hinged seat at an inclination thereto in a way to secure the desired results.

The object of this invention is to produce a comfortable desirable and serviceable sofa bed of this type in which like results are attained by a simple and inexpensive construction in which the outer section of the folding bed bottom is movably mounted on the underside of the hinged seat, so as to be supported horizontally above the seat when 45 the latter is inverted and to assume an inclined position under the seat in the normal position thereof.

In the accompanying drawings: Figure 1 is a sectional elevation of a sofa bed embodying the invention, showing the same

closed for use as a couch. Fig. 2 is a fragmentary sectional elevation of the bed bottom and mattress folded. Fig. 3 is a fragmentary longitudinal section on line 3—3, Fig. 6. Fig. 4 is a sectional elevation of the sofa bed opened for use as a bed. Fig. 5 is a fragmentary elevation, partly in section, of the inverted seat showing the supporting leg therefor. Fig. 6 is a fragmentary plan partly in horizontal section of the sofa bed 65 opened.

Like reference characters refer to like parts in the several figures.

The stationary frame A of the couch and the hinged seat B may be constructed and 70 hinged together in any usual or suitable way, adapting the seat to be turned forwardly from the normal position, shown in Fig. 1, in which it forms the seat of the couch, to the inverted position in front of the stationary frame, shown in Fig. 4.

A couch of the davenport type is shown in the drawings and the frame consists of upright end pieces a connected at the lower portion by front and back rails a' a'', and 80 by a stationary upholstered back a³. In the construction shown the front and back rails a' a'' of the frame are connected by end rails a⁴, thus forming a rigid rectangular base frame to which the separate upright end 85 pieces a are attached, but while this construction is preferred, it is not essential.

The couch seat B preferably consists, as shown, of a rectangular box-like wooden frame b containing suitable springs b' which 90 form a spring bottom for the upholstered seat pad or covering b². The seat is hinged to the stationary frame by ordinary hinges C connecting the lower edge of the front board of the seat frame to the upper edge 95 of the front rail a' of the stationary frame.

The folding bed bottom consists of a two-part folding rectangular metal frame and the usual resilient fabric D of flexibly connected links, or other formation, which is attached at opposite ends to the folding ends of the frame. The folding bed bottom frame is composed of an outer section d and an inner section d', each of substantially U-shape, the extremities of the end bars of which are hinged together and to suitable rigid standards or supports E projecting from the seat frame at the ends of the front or hinged side thereof, in such a manner as to adapt the bed bottom frame to fold under 105 110

the seat and the outer section thereof to also swing upwardly toward the seat to the inclined position, shown in Fig. 1, when the seat is turned to its normal seat-forming position. In the construction shown the two sections of the bed bottom frame are hinged to each other by a pair of common hinges *e* and the outer section *d* is hinged to the standards *E* by another pair of common hinges *e'*, but any other suitable hinge connections which will permit the above mentioned movements of the frame sections can be employed. The standards *E* shown consists of pieces of wood rigidly fastened to the front board of the seat frame and braced by corner blocks *e²*, but they can be constructed and rigidly secured to the seat frame in any other suitable way.

Swinging links *F* pivoted to the ends of the seat frame and having studs or rollers entering slide ways *f* on the end bars of the outer bed bottom section, or which are otherwise slidably connected therewith, coöperate with the standards *E* in supporting said outer bed bottom section in a horizontal position above the couch seat when the seat is inverted. The links *F* are moved to and retained in the upright supporting position by suitable means, such as springs *f'* connecting them to the seat frame. In swinging the couch seat from its inverted position to its normal position, cam shaped portions of the links *F* strike projections *f²* on the ends of the couch frame and are thereby swung upwardly out of their holding position, and act to swing the outer bed bottom section upwardly on its hinges to the inclined position shown in Fig. 1.

The inner bed bottom section, in the couch illustrated, is movably supported by a link *G* pivoted to each end of the couch frame and slidably connected to the adjacent end bar of said inner section *d'*, and an actuating link *g* is pivoted to each end of said inner section and slidably connected to the adjacent supporting link *G*.

In the normal position of the couch seat the inner section *d'* of the bed bottom is supported beneath the outer section *d* by its hinge connections with the outer section and by suitable brackets *h* on the stationary frame, as shown in Fig. 1. When the seat is inverted the supporting links *G* are raised by the links *g* to the position shown in Fig. 50 4, and support the inner bed bottom section in a horizontal position in the same plane as the outer section. The inner bed bottom section can, however, be supported by any other suitable connections permitting it to 55 assume the positions mentioned.

The couch seat can be supported in its normal and inverted positions by any suitable means. For instance, blocks *i* on its ends rest on the ends of the stationary frame 60 to support it in the normal position, and a

leg *I* pivotally or slidably mounted in a socket *i'* at each end of the couch seat supports it in the inverted position. When inverting the seat these legs swing to an upright position and slip up into the sockets whereby they are held rigid and support the seat, and when the seat is swung back to its normal position the legs swing back out of sight between the ends of the seat and the ends of the couch frame.

K represents springs attached to the standard *E* and to the end of the couch frame for assisting in raising the couch seat when swinging it to and from its normal position. These springs, or any other suitable means for the purpose, can be employed or not, as preferred.

By employing a folding bed bottom composed of two sections with the outer section mounted as described on the hinged couch seat, and the inner section hinged to the outer section and mounted to raise and lower in the couch frame, ample space is left between the sections, when folded, for the folded mattress, and when the bed bottom is unfolded or extended for use as a bed, it is supported well above and free from the frame of the couch seat and the front rail of the stationary frame, so that there is nothing to prevent the bottom fabric from yielding to the extent necessary to insure an easy comfortable bed. When the bed bottom is folded the sections of the frame diverge at an angle from their hinge connections, but the bottom fabric between the end bars of the frame will spread and conform to the folded mattress, as indicated in Fig. 2, and the mattress does not have to be crushed or compressed at the fold. The short intermediate section heretofore used in the bed bottom frame is, therefore, not necessary. It will be observed that, by the construction described the couch seat can be made with an ordinary box frame of wood connected by ordinary hinges to the stationary couch frame, and the bed bottom frame has but two sections. The structure is composed of but few parts and hinges and connections of special design are not required. Since the bed bottom fabric is attached to the ends of the bottom frame by springs, which are under considerable tension, the fabric exerts a strong inward pull on the folding ends of the bottom frame, which is, of course, increased by the weight of a person on the bed, and in the three piece constructions special provision has to be made to prevent the ends of the frame from bending inwardly and causing the fabric to sag. With the bed bottom frame composed of the two hinged sections, one hinged to rigid parts on the couch seat as described, the ends of the frame are effectually held against the inward pull of the fabric. When the bed bottom is extended the rear edge of the inner section 125

lies close to the back of the couch, and does not leave the wide space between the bed bottom and the back of the couch which is a serious objection in many constructions.

5. I claim as my invention:

1. The combination of a couch frame, a couch seat hinged to said frame so that it can be inverted in front of said frame, a two-part folding bed bottom comprising 10 movably connected outer and inner frame sections, means which movably connect said outer section to said seat and support said section above and spaced from the seat when the latter is inverted and permit said section 15 to assume an inclined position beneath the seat when the latter is in its normal position, and means which support said inner section in the horizontal plane of said outer section when the bed bottom is extended and 20 permit the inner section to assume a position below the outer section when the bed bottom is folded, substantially as set forth.

2. The combination of a couch frame, a couch seat hinged to said frame so that it can be inverted in front of said frame, a two-part folding bed bottom comprising 25 movably connected outer and inner frame sections, and means which movably connect said inner and outer bed bottom sections 30 respectively to said couch frame and to said seat and support said inner and outer sections horizontally in a plane above and spaced from the seat when the latter is inverted and permit said sections to assume 35 positions in which they diverge rearwardly from each other beneath said seat when the latter is in its normal seat-forming position, substantially as set forth.

3. The combination of a couch frame, a couch seat hinged to said frame so that it can be inverted in front of said frame, a two-part folding bed bottom comprising 40 inner and outer frame sections which are movably connected to each other and to said seat, links which connect said outer section to said seat and support said section in a horizontal position above and spaced from the seat when the seat is inverted and permit said section to swing to an inclined position relative to the seat when the seat is moved to its normal position, and means 45 which support said inner section in the horizontal plane of said outer section when the bed bottom is extended and permit the inner section to assume a position below the outer 50 section when the bed bottom is folded, substantially as set forth.

4. The combination of a couch frame, a couch seat hinged to said frame so that it can be inverted in front of said frame, said 55 seat having rigid bed bottom supports at its ends, a two-part folding bed bottom com-

prising inner and outer frame sections hinged to each other and to said rigid supports on the seat, links which connect said outer section to said seat and support said section in a horizontal position above and spaced from the seat when the seat is inverted and permit said section to swing to an inclined position relative to the seat 65 when the seat is moved to its normal position, and means which support said inner section in the horizontal plane of said outer section when the bed bottom is extended and permit the inner section to assume a position 70 below the outer section when the bed bottom is folded, substantially as set forth.

5. The combination of a couch frame, a couch seat hinged to said frame so that it can be inverted in front of said frame, a two-part folding bed bottom comprising 75 inner and outer frame sections which are movably connected to each other and to said seat, links which connect said outer section to said seat and support said section in a horizontal position above and spaced from the seat when the seat is inverted, parts on 80 said couch frame which engage said links and swing said outer section to an inclined position relative to the seat when the seat is moved to its normal position, and means which support said inner section in the horizontal plane of said outer section when the bed bottom is extended and permit the inner 85 section to assume a position below the outer 90 section when the bed bottom is folded, substantially as set forth.

6. The combination of a couch frame, a couch seat hinged to said frame so that it can be inverted in front of said frame, a two-part folding bed bottom comprising 95 inner and outer sections which are movably connected to each other and to said seat, links which connect said outer section to 100 said seat, springs which raise said links to support said section in a horizontal position above the seat when the seat is inverted, parts on said couch frame which engage said links and swing said outer section to an inclined position relative to the seat when the seat is moved to its normal position, and means which support said inner section in the horizontal plane of said outer section 105 when the bed bottom is extended and permit the inner section to assume a position below the outer section when the bed bottom is folded, substantially as set forth.

Witness my hand this 1st day of February, 1912.
